Inventor:

Clarence A. Walkwitz,

By *Samuel N. Bond City*

UNITED STATES PATENT OFFICE.

CLARENCE A. WALKWITZ, OF OLD HICKORY, TENNESSEE.

SLEEPER ANCHOR.

Application filed March 30, 1925. Serial No. 19,194.

This invention relates to a class of building appliances commonly known as sleeper anchors, designed to anchor a floor joist or sleeper to an underlying body of concrete.

5 A common form of these devices comprises a generally U-shaped saddle embracing the bottom and sides of the sleeper and nailed or otherwise attached to the latter, and means associated with the saddle for anchoring the latter to the concrete. In the use of these devices, the sleeper anchors are set on the concrete in longitudinal rows corresponding with the positions of the sleepers, and the anchoring devices are pressed into the 10 plastic concrete before the latter has set. The sleepers are then laid in the saddles, and the sides of the latter are then nailed or otherwise attached to the sleeper before the superposed flooring is laid. When the 15 concrete hardens, the anchors are, of course permanently attached to the concrete and they, in turn, bond the sleepers securely to the concrete.

20 The principal object of my present invention is to provide a very simple, inexpensive and efficient sleeper anchor of the character described. More specific objects are to provide an anchor having readily collapsible sides and anchor prongs, whereby the manu-

25 factured articles can be packed and shipped in stacked form requiring but a minimum of space; to provide a sleeper anchor having side walls which may be easily folded into nailing position against the sides of the 30 sleeper or joist; and to provide a sleeper anchor equipped with anchoring prongs of such a form as to afford a very tenacious hold on the concrete.

35 Other objects and attendant advantages 40 of the invention will be apparent to persons skilled in the art as the same becomes better understood by reference to the following description, taken in connection with the accompanying drawing, wherein I have 45 illustrated a practical and approved embodiment of my improved sleeper anchor, and in which—

50 Fig. 1 is a plan view showing the saddle member in open or unfolded position and the anchoring prongs lying in the plane of the bottom plate of the saddle, ready to be bent down to working position;

55 Fig. 2 is an end elevation showing the anchor secured to a sleeper; and

Fig. 3 is a fragmentary vertical section of a complete floor, including the concrete in

which the anchors are set, a sleeper or joist mounted in the anchors, and superposed flooring.

Referring to the drawings, the improved 60 sleeper anchor of my invention is preferably made of sheet-metal, and includes a generally U-shaped saddle which, as herein shown, comprises a flat rectangular bottom plate 5, and flat rectangular side plates 6 65 that are preferably hinged at their lower edges to opposite edges of the bottom plate by a well-known standard form of hinge comprising integral sleeves 7 on the side plates 6, integral sleeves 8 on the bottom 70 plate 5 between and alined with the sleeves 7, and hinge rods or pintles 9 extending through said sleeves. Preferably, and as herein shown, the hinges are so formed that, when the side plates are swung upwardly 75 for attachment to the sides of the sleeper, they are disposed externally of the U-shaped saddle thus formed, thus enabling the sleeper to snugly fit both the bottom and side walls of the saddle as shown in Fig. 2. 80

In the bottom plate 5 are cut a pair of anchor prongs 10, the preferred form of which is clearly shown in Fig. 1, wherein it will be seen that each prong is formed at its lower end with a widened or barbed head 10'. Prior to the setting of the anchor in the concrete, the two prongs 10 are bent downwardly on the dotted lines 11 (Fig. 1) to approximately vertical position. It will be observed that both prongs are located 85 wholly inwardly of the longitudinal and transverse edges of the bottom plate 5, and are both longitudinally and transversely offset, so that the marginal portions of the bottom plate for a considerable thickness are 90 left integral or uncut, whereby only a minimum weakening of the plate is caused by the cutting and bending therefrom of the anchor prongs.

In the practical use of the device the anchors are set at substantially uniformly spaced intervals in the body of concrete C while the latter is still soft enough to permit the anchor prongs 10 to be pressed down 100 therein. The sleeper S is then laid upon the bottom plates of the row of anchors, and the side walls 6 of the latter are then folded up against the sides of the sleeper and attached thereto by nails 12. The flooring F 105 may then be nailed to the sleepers.

When the concrete is set, the anchors are 110 very strongly held therein by reason of the

barbed character of the anchor legs 10; while the feature of the foldable hinged sides 6 facilitates the rapid laying of the sleeper as compared with structures wherein 5 the side walls of the saddle are more or less rigid with the bottom wall and sometimes require to be spread more or less before the sleeper can be entered therebetween. Another advantage resulting from making the 10 sides 6 foldable resides in the fact that in building operations a considerable interval of time frequently intervenes after the anchor is set in the wet concrete until the sleepers and floor are laid. During this 15 period a lot of work is going on and men and wheelbarrows are moving over the concrete, and if the side walls of the sleeper anchors were left sticking upward they would frequently be bent down or knocked 20 off. In the construction herein shown it is manifest that the side walls can be folded

down and remain closed in a horizontal position until the time when the sleepers are to be set, which entirely obviates the objections above-noted. 25

Manifestly the device is capable of rapid and economical manufacture by punch press methods from a stock of sheet-metal, and wire to form the hinge pintles 9, and the increment of total building cost represented 30 thereby is so low as to be practically negligible.

I claim—

A sleeper anchor, comprising a U-shaped sheet-metal saddle having a flat rectangular bottom plate and foldable flat rectangular side plates hinged to opposite edges of said bottom plate, and one or more barbed anchoring prongs cut out of and bent downwardly from said bottom plates. 35

CLARENCE A. WALKWITZ.
